UNITED STATES PATENT OFFICE.

JAMES J. DICKS, OF TORONTO, CANADA.

HAMMOCK.

SPECIFICATION forming part of Letters Patent No. 445,049, dated January 20, 1891.

Application filed July 2, 1890. Serial No. 357,504. (No model.)

To all whom it may concern:

Be it known that I, JAMES JOHN DICKS, builder, of the city of Toronto, in the county of York, in the Province of Ontario, Canada, 5 have invented a certain new and useful Improvement in Hammocks, of which the following is a specification.

The object of the invention is to provide a hammock with a detachable sunshade; and 10 it consists, essentially, of a sunshade or hood connected to a stretcher and attached to the head of the hammock, substantially as hereininafter more particularly explained, and then definitely claimed.

15 Figure 1 is a perspective view of a hammock provided with my improved sunshade. Fig. 2 is a bottom view of a portion of the stretcher, showing the clip for connecting it to the hammock. Fig. 3 is a perspective 20 view of a portion of the stretcher, showing the tail of a portion of the stretcher, showing the clip to which the pillow is connected.

In the drawings, A represents a stretcher fitted into the hammock B, and provided with spring hooks or catches a, which are designed 25 to engage with the strands of the hammock and hold the stretcher in the position indicated.

C is a flat plate pivoted on the stretcher A, so that it may be folded in parallel with the 30 said stretcher when the hammock, with its hood, is done up for transportation, or set in the position indicated in Fig. 1 to prevent the stretcher tilting.

On the top side of the stretcher A, I provide hooks b, to which the loops on the pillow 35 may be attached for the purpose of holding the said pillow in position.

D is a sunshade or hood pivoted, as indi-

cated, on the top of the stretcher A, tapes or cords E being attached to the said sunshade 40 D for the purpose of tying it to the hammock B.

A sunshade or hood arranged as described, in connection with the stretcher mentioned, will remain in position and may be readily 45 adjusted by the occupant of the hammock, so as to be raised or lowered to give more or less air or shade. By raising the front bow more air will be given and less shade, while the reverse will of course be the case if the bow is 50 lowered. This raising or lowering will be readily accomplished because the bows are pivotally connected to the stretcher, and the friction of the joints will retain the bow in the desired position. 55

What I claim as my invention is—

1. A stretcher A, provided with hooks a to engage with the hammock B, and a plate C, pivoted on the said stretcher, in combination with a sunshade or hood D, pivoted on the 60 stretcher, substantially as and for the purpose specified.

2. A stretcher A, provided with hooks a to engage with the hammock B, hooks b, to which a pillow may be connected, and a plate C, 65 pivoted on the said stretcher, in combination with a sunshade or hood D, pivoted on the stretcher A and provided with tapes or cords E, connected to the hammock, substantially as and for the purpose specified.

Toronto, June 11, 1890.

JAMES J. DICKS.

In presence of—

CHARLES C. BALDWIN,
E. CUMMINGS.
